UNITED STATES PATENT OFFICE.

ROBERT HOWARD BIGGS, OF ST. CATHARINES, CANADA.

COMBINATION STRING HOLDER AND ADVERTISING DEVICE.

Application filed August 3, 1922. Serial No. 579,468.

To all whom it may concern:

Be it known that I, ROBERT HOWARD BIGGS, a subject of the King of Great Britain, and a resident of the city of St. Catharines, in the county of Lincoln, in the Province of Ontario, Canada, have invented certain new and useful Improvements in Combination String Holders and Advertising Devices, of which the following is the specification.

My invention relates to improvements in combination string holders and advertising devices and the object of the invention is to devise a string holder from which the string may be withdrawn so as to exhibit a new advertisement at each operation and it consists essentially of the following arrangement and construction of parts as herein-after more particularly explained.

Fig. 1 is a face elevation of my string holder and advertising device.

Fig. 2 is an enlarged face sectional view through Fig. 1.

Fig. 3 is a cross sectional view through the center of Fig. 2.

Fig. 4 is a sectional plan view on line 4—4, Fig. 2.

Fig. 5 is a further enlarged detail of the main bearing sleeve.

Fig. 6 is a perspective detail of the pad holder employed in connection with my device.

In the drawings like characters of reference indicate corresponding parts in each figure.

1 indicates the base of my machine. 2 and 3 are casing members supported upon the base, the member 3 being secured thereto by screws 4. The lower portion 3^x of the base forms a housing in which the string is contained as will hereinafter appear.

The upper portion of the casing 3° is substantially circular and is connected to the portion 3^x by a hollow neck 3¹. 5 and 6 are orifices formed in the center of the circular portion 3° of each casing member 2 and 3, the orifices 5 and 6 being in horizontal alignment. 7 is a stud provided with reduced threaded ends 8 and 9 and extending through the orifices 5 and 6.

10 is a reduced portion located intermediate of the length of the stud 7, the periphery of such reduced portion being formed with ratchet teeth 11 for a purpose

12 and 13 are securing nuts which are screwed onto the reduced threaded portions 8 and 9 to secure the stud 7 in a stationary position within the casing. 14 is a circular enlargement adapted to bear against the inner face of the casing member 3, such casing member being clamped between the enlargement 14 and the nut 13. Each casing member 2 and 3 is provided with a central internal recess 15 which is concentric with the center of each orifice 5 and 6. 16 is a sleeve which is mounted upon the stud 7, such sleeve being provided, intermediately of its length, with a segmental cutaway portion 17 located opposite the reduced portion 10 of the stud 7.

The sleeve 16 is provided with reduced externally threaded ends 16^x and 16°. 18 and 19 are discs provided with internally threaded central orifices 18^x and 19^x through which the reduced ends 16^x and 16° of the sleeve 16 pass. 20 and 21 are discs of card or other suitable material upon which suitable advertisements are inscribed for a purpose which will hereinafter appear. The disc 18 is provided in its peripheral edge with ratchet-shape notches 22 spaced at suitable distances apart.

23 is a stud extending from the casing member 3 towards the center of the machine. 24 is a dog swung upon the stud 23 and adapted to engage with the ratchet notches 22 being spring-pressed into engagement with such notches by the spring 25. 26 is a pin extending outward from the dog 24.

27 is a pulley member formed by a disc portion having radial slits 28 extending inward from the edge thereof to form a series of tongues 29 which are bent alternately in opposite directions to form a string receiving V-shape groove 30. 31 and 32 are bearing brackets secured to the base 1 within the casing formed by the members 2 and 3. 33 is a shaft secured within the orifices 34 and 35 of the brackets 31 and 32. 36 is a sleeve mounted freely upon the shaft 33 and upon which is forced a ball of string as indicated at 37.

The strand 38 of the ball 37 passes upward around the pulley 27 and outward through an orifice formed by opposing notches 39 and through an orifice 40 formed in a guide finger 41 secured to the casing member 3 as indicated at 42. The bracket 32 is provided with an upward extension 110

43 from which extends a horizontal finger 44 having a guide orifice 45 in proximity to the end thereof through which the strand of string 38 passes and whereby the string 5 is held to track with the pulley 27.

The base portion 3* of the casing is provided with an extension 46 formed by vertical wall portions having inclined edges 47. 48 is a stud extending between the wall portions of the extension 46. 49 is a pad holder. 10 The pad holder 49 comprises a plate 50 adapted to fit between the inclined edges 47 and a horizontal extension 51 which is broad U-shape in cross section, the arms of 15 the U being provided with inverted notches 52 adapted to fit over the stud 48 so as to form a support for the pad holder. 53 are the leaves of the pad which are secured upon spicular projections 54. 55 are exhibiting 20 orifices formed in the casing members 2 and 3.

The exhibiting orifices 55 are provided with transparent window portions 56. 57 are fingers rigidly secured to the pulley 27 25 so as to project outward therefrom. The outer end of each finger is provided with an inclined portion 58 adapted to engage the pin 26 when the pulley 27 is revolved.

Having described the principal parts involved in my invention I will briefly 30 describe the operation of the same.

When it is desired to tie a parcel the string strand 38 is grasped at its free end by the operator and pulled outward from 35 the casing through the orifices 39 and 40.

By this means the pulley 27 is revolved as the string is drawn off the ball 37.

As the pulley 27 is revolved the inclined end 58 of one of the finger projections 57 40 engages the pin 26 lifting the dog 24 out of the notch 22 with which it is in engagement. 59 is a helical spring, one end of which is secured to the hub of the pulley 27 and the other end to the disc 18.

45 When the strand of string is pulled in the manner above described to rotate the pulley 27 the spring 59 is gradually tightened, the disc 18 being held from rotation by the dog 24. As the pulley 27 is turned 50 the inclined portion 58 of the finger 57 next adjacent to the dog 24 engages the pin 26 thereby lifting the dog 24 out of engagement with the notch 22 with which it is engaged thereby freeing the disc 18 which is 55 then carried by the spring in tension a partial turn to exhibit the next succeeding advertisement through the orifice 55. The disc 19, being mounted upon the same sleeve as the disc 18, turns in unison so as to also 60 exhibit the next succeeding advertisement through the orifice 55 of the casing member 2.

In order to prevent the return of the pulley 27 after each outward draw upon the 65 strand of string 38 I have provided a dog

60 pivoted upon a pin 61 carried by the pulley 27. The dog 60 coacts with the ratchet 11 sliding over the ratchet during the forward turning movement of the pulley 27 to engage with the ratchet teeth on any 70 tendency for the pulley 27 to make a return movement.

The casing member 3 may be provided with a socket 62 for the reception of the pencil 63 by which the addresses to which 75 the parcels are sent may be noted upon the pad 53.

From this description it will be seen that I have devised a very simple device adapted to hold string so that the string may be 80 readily drawn off from the wall and which, by such operation, will automatically operate an advertising device so that a new advertisement is exhibited by each operation.

What I claim as my invention is:

1. In a combination string holder and advertising device, a casing, a mounting located within the casing and upon which a ball of string is turnably carried, a pulley member mounted within the casing to rotate in a vertical plane above the mounting of the ball of string and over which the free strand of the string is adapted to pass, a turnable member having a face set vertically and bearing a series of advertisements on such face adapted to be successively carried by the turnable member from an unexposed to an exposed position, and means for automatically operating the turnable member as each length of string is drawn off the ball 90 around the pulley.

2. A combination string holder and advertising device comprising a casing having an exhibiting orifice, a mounting located within the casing upon which the ball of string is turnably carried, a pulley also mounted within the casing above the ball of string and around which the free end of the string strand is adapted to pass, a disc having its face set vertically also turnably mounted within the casing adapted to carry a series of advertisements on such vertical face, and means for automatically turning the disc after each length of string is drawn off around the pulley to carry each advertisement to an exposed position opposite the exhibiting orifice.

3. A combination string holder and advertising device comprising a casing, a mounting located within the casing upon which a ball of string is turnably carried, a stud extending through the casing at right angles to the aforesaid mounting, a pulley mounted thereon around which the strand of string passes from the ball, a disc also mounted upon the stud independently of the pulley and adapted to bear a series of advertisements to be brought successively from an unexposed to an exposed position, a resilient connection between the disc and the pulley,

- releasable means for holding the disc in a stationary position, and means for automatically freeing the disc at the end of each turning movement of the pulley.
6. A combination string holder and advertising device comprising a casing, a mounting located within the casing upon which a ball of string is turnably carried, a stud extending through the casing at right angles to the aforesaid mounting, a pulley mounted thereon around which the strand of string passes from the ball, a disc also mounted upon the stud independently of the pulley and adapted to bear a series of advertisements to be brought successively from an unexposed to an exposed position, a resilient connection between the disc and the pulley, releasable means for holding the disc in a stationary position, means for automatically freeing the disc at the end of each turning movement of the pulley, and means for preventing the return movement of the pulley after each operation.
5. A string holder and advertising device comprising a casing, a mounting located in the lower portion of the casing and adapted to carry a ball of string, a stud shaft secured in the casing, a sleeve mounted upon the stud shaft, a pulley mounted freely upon the sleeve and around which a strand of string from the aforesaid ball is adapted to pass, a disc secured to each end of the sleeve and each bearing a series of advertisements adapted to be brought from an unexposed to an exposed position, raisable means engaging the periphery of the disc to hold it from rotation, means carried by the pulley adapted to raise such raisable means to free the disc, and a resilient connection between the pulley and the disc adapted to exert a tension upon the disc as the pulley is turned prior to the raising of the raisable locking means.
6. A combination string holder and advertising device comprising a casing, a ball string mounting located in the lower portion of the casing, a stud extending through the casing and set at right angles to the aforesaid mounting, a sleeve mounted upon the stud, a pulley freely mounted upon the sleeve, a disc secured to each end of the sleeve, each disc bearing a series of advertisements adapted to be brought from an unexposed to an exposed position, one of said discs having a series of peripheral ratchet notches, a dog carried by the casing and co-acting with the notches to hold the disc stationary, a finger carried by the pulley adapted to raise the dog out of engagement with the notch as the pulley is turned, and a resilient connecting means between the pulley and the disc adapted to be drawn into tension as the pulley is turned prior to the release of the dog.
7. A combination string holder and advertising device comprising a casing, a mounting for a ball of string located in the lower portion of the casing, a stud extending through the casing at right angles to the ball of string, a ratchet cut in the stud, a sleeve mounted upon the stud and having a segmental orifice, a pulley mounted upon the sleeve, a dog carried by the pulley and adapted to pass through the aforesaid sleeve to engage the ratchet, a member carried by the sleeve and adapted to bear a series of advertisements adapted to be successively brought to an exposed position, and means operated by the turning of the pulley for turning the disc after each length of string has been drawn around the pulley.

ROBERT HOWARD BIGGS.
